Primary Examiner — Bao-Yen T Nguyen*Assistant Examiner* — Loryn K. LeBlanc(74) *Attorney, Agent, or Firm* — Bayramoglu Law Offices LLC(57) **CLAIM**

The ornamental design for a camera stabilizer, as shown and described.

DESCRIPTION

FIG. 1 is a perspective view of a camera stabilizer showing our new design;

FIG. 2 is a front view thereof, a rear view being a mirror image of the front view;

FIG. 3 is left side thereof;

FIG. 4 is a right side view thereof;

FIG. 5 is a top view thereof; and,

FIG. 6 is a bottom view thereof.

The broken lines depict portions of the camera stabilizer that form no part of the claimed design.

1 Claim, 6 Drawing Sheets(56)
